HAND MOP

Leonard Jones, Jackson, Miss., assignor to
R. E. Warwick, Jackson, Miss.

Application March 24, 1950, Serial No. 151,672

3 Claims. (Cl. 15—227)

1

The present invention relates to new and useful improvements in mops and more particularly to a hand or mitten mop.

An important object of the invention is to provide a canvas or other fabric back for the mop to which the mop material is sewed and forming the back with a pocket in which a rigid wire frame is placed to hold the material of the back taut.

Another object is to provide a hand strap constructed of an endless elastic band held on the back of the mop by the frame.

A further object is to provide a protective rubber band surrounding the edges of the mop to hold it to the frame and which protects the fabric from wear as well as protecting the work from damage by the frame.

A still further object is to provide a mop of simple and practical construction, which is relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a perspective view of the wire frame and hand strap;

Figure 3 is a perspective view of the protective band;

Figure 4 is an enlarged longitudinal sectional view taken on a line 4—4 of Figure 1;

Figure 5 is a transverse sectional view taken on a line 5—5 of Figure 4; and

Figure 6 is a perspective view of the back of the mop and pocket therein having the mop strands removed therefrom.

Referring now to the drawing in detail, wherein for the purpose of illustration I have disclosed a preferred embodiment of my invention, the numeral 5 designates the back of the mop and which is constructed of canvas or other suitable flexible fabric and of substantially triangular shape to form a narrow front end 6. A front hand pocket is formed when similar material 7 is sewed to the edges of the front end with an entrance 8 positioned transversely of the back adjacent its center.

A binding 9 also of canvas is sewed to the rear and side edges of the back rearwardly of the pocket and overlies the back at its rear corners to form shallow pockets 10 at the rear of the mop. The mop strands of mop material 11 are sewed to the edges of pocket material 7 and binding 9.

2

Figures 4 and 5 show the peripheral attachment of the mop strands 11 to the edges of the back 5 and to the front and rear pocket forming material. In Figure 5 the strands 11A are shown looped and stitched to the back 5 running substantially the length of the mop and spaced upon either side of a centerline running from the front of the mop to the rear of the mop.

A triangular shaped wire frame 12 is inserted in front hand pocket formed by the material 7 and rear corner pockets 10 to stretch and hold the back taut and an endless elastic band 13 is placed over the sides of frame 12 to form a hand strap 14 extending across the top of the back of the mop rearwardly of entrance 8 to pocket 7. The top of the pocket material 7 prevents the band 13 from creeping forwardly on the frame 12.

An endless elastic protective binding 15, preferably of rubber, encloses the sewed edges of 20 mop strands 11, as well as the edges of front pocket material 7 and the edges of canvas binding 9 forming the rear pockets 10 to protect the entire edges of the mop from wear and to prevent marring of the surface on which the mop is used 25 by the hard frame 12. The rubber protective binding 15 is enlarged at the corners of the mop to form resilient bumpers 16.

In using the mop, the hand of a person is inserted under strap 14 and into front pocket formed by the material 7 to hold the mop on the hand.

Having described the invention, what is claimed as new is:

1. In a hand mop the combination including: 35 a back of flexible material and of substantially triangular shape to form a narrow front end; a flexible material on top of said back and secured to the edges thereof at the front end to form a pocket; flexible binding material on top of said back at its rear corners and bound to said back forming rear shallow pockets; a substantially triangular shaped wire frame holding said back taut and positioned in the pockets formed by said flexible material bound to said back; mop material secured peripherally to the said binding material and said flexible front pocket material; and a separate resilient detachable protective binding covering the edges of said back where the said front and rear pocket material is bound thereto, and having enlarged bumper forming portions at the corners of said frame.

2. In a hand mop the combination including: 45 a back of flexible material and of substantially triangular shape to form a narrow front end; flexible material on top of said back and secured to the edges thereof at the front end to form a

front pocket; flexible binding material on top of said back at its rear corners and bound to said back forming rear shallow pockets; a substantially triangular shaped wire frame holding said back taut and positioned in said pockets formed by said flexible material bound to said back; an endless elastic band encircling said frame rearwardly of said front pocket; mop material secured peripherally to the said binding material and flexible front pocket material; and a separate resilient detachable protective binding covering the edges of said back where the said front and rear pocket material is bound thereto and having enlarged bumper forming portions at the corners of said frame.

3. In a hand mop according to claim 2, wherein said flexible material forming said front pock-

et includes a stop at the entrance of said front pocket to prevent forward creeping of said band on said frame.
